W. F. Gisby

Inventor:
Raymond F. Barnes
By Parker W. Page, Acty.

UNITED STATES PATENT OFFICE.

RAYMOND F. BARNES, OF BROOKLYN, NEW YORK.

CHANDELIER.

SPECIFICATION forming part of Letters Patent No. 323,625, dated August 4, 1885.

Application filed February 24, 1885. (No model.)

To all whom it may concern:

Be it known that I, RAYMOND F. BARNES, a citizen of the United States, residing at Brooklyn, in the county of Kings and State 5 of New York, have invented certain new and useful Improvements in Chandeliers, of which the following is a specification, reference being had to the drawings accompanying and forming a part of the same.

10 My invention is an improvement in chandeliers; but since the said improvements relate more especially to chandeliers for supporting incandescent electric lamps, or such as are known as "electroliers," I have illustrated them as applied to such a devi-

15 Broadly stated, my invention consists in a lamp-holder adapted for use either as a drop-light or as a stand or desk lamp, which is connected with the main portion of the chandelier by a flexible cable or tube, as the case may require, and containing a reel or equivalent device for taking up the cable or tube, whereby the lamp and holder may be used, at any desired elevation with reference to the chandelier with which it is connected or used, as a stand-lamp upon a desk or table.

20 In carrying out my invention I employ a hollow casing with a base, by means of which it may be placed in an upright position upon a table, and to said casing I attach suitable 25 arms or a frame for carrying the lamp and permitting the same to be reversed in position. Within the casing I provide a spring-actuated reel, upon which is wound a stout 30 cable containing the insulated wires. This cable is carried out through the base and connected to the chandelier, the wires being carried up through the casing below the vertical 35 tube or support and connected with the wires within the chandelier. The base of the lamp- 40 holder is made in such form that when held up against the casing of the chandelier by the connecting-cord it presents the appearance of a single fixture. The reel is provided with 45 some form of locking device, by which the lamp may be held at any desired elevation as a drop-light, or which will prevent the cord from being wound up when a sufficient length 50 has been reeled off to permit the holder to be used as a stand-lamp.

While I prefer to place the reel within the lamp-holder, it is obvious that without ma-

terial change it could be placed within the casing of the chandelier.

The particular device by which my invention is best carried into effect is illustrated in 55 the accompanying drawings.

Figure 1 is a side elevation of a portion of a chandelier with my improvements applied thereto. Fig. 2 is a central vertical section of 60 the lower portion of the chandelier, the lamp-holder, and parts of the lamp-supporting frame. Fig. 3 is a sectional detail of one of the joints of the lamp-frame. Fig. 4 is a side 65 view of the same, and Fig. 5 is a sectional view of the spring-reel.

A designates a chandelier or similar support having one or more arms, B, carrying incandescent lamps.

The interior tube, C, containing the wires, 70 supports the body of the chandelier and its lateral branches C', which extend from a chamber, D. From this chamber extends also a short tube, E. Through the lateral tubes the conducting-wires are carried in the usual manner, and a two-wire cable, F, or stout flexible cord containing two insulated conductors, is carried up into the tube E, where it is properly secured and its wires connected with the conductors c. A casing, G, surrounds the 75 tubes C, C', and E, as is usual in such chandeliers.

H is a metal casing provided with a base, K. Within the casing is a reel, L, with which is combined a volute spring, S, a ratchet-wheel, h, and a spring-pawl, l, pivoted to the casing, and controlled by a pin, h', extending through the casing. Around this reel the flexible cord or cable F is wound, its end being firmly secured to the shaft or to one of the 80 flanges of the reel, and its insulated wires being electrically connected with bands of metal f, carried by the shaft, but insulated from the same.

Above the reel L two guide-rollers, M, are placed, and the cord F is passed between these, so that it is held in proper position for supporting the lamp-holder vertically, and is properly reeled when the lamp-holder is raised or lowered.

To the end of casing H is secured the branching frame N, formed of metal tubes bent in any suitable manner. To the ends of these tubes is joined the bow O, also formed

of a tube, and to the middle joint of this is secured a lamp-socket and a shade, P.

Springs *m m* bear upon the insulated metal rings *f* on the shaft of the reel *L*, and from 5 these insulated wires are run through the arms *N* and bow *O* to the lamp supported thereby. In this way a path for the current from the wires in the chandelier to the lamp is provided for, whatever may be the position 10 of the lamp-holder. The bow *O* is united to the arms *N* by any form of joint that permits the bow to be turned a half-revolution without disturbing the electrical connections. A simple form of joint is shown in Figs. 3 and 15 4, in which a projection from a knob, *o*, on the bow *O* turns in a socket formed on a similar knob, *o'*, at the end of arm *N*. A tooth, *p*, on one member of the joint enters notches in the other and holds the bow in either of the two 20 positions shown in Fig. 1. The arms *N* act as springs, having sufficient force to retain the bow in the position in which it may be set.

A pin, *T*, is passed through the axial line of each joint, and around this the conducting- 25 wire is wound in a loose spiral, so that the bow may be turned without injuring the wire. The bow should be prevented from turning more than one-half a revolution, for which purpose any convenient form of stop may be 30 used—such as a knob, *t*, on the frame *N*, that projects into the path of the bow *O* or any projecting part thereof.

When the lamp is to be used as a drop-light, the bow, with its lamp and shade, is set 35 as in Fig. 2, and the holder raised until the base *K* comes in contact with the casing of the chandelier. In this position it is held by the pawl *l*. The lamp may also be suspended at any other desired elevation by the cord, it being only necessary to depress the pin *h* until 40 the lamp is raised or lowered to the proper point. If the lamp is to be used as a stand-lamp, the bow is turned over, as shown in dotted lines in Fig. 1, and a sufficient length of 45 cord drawn out to permit the holder being reversed and placed on a table or desk.

The device as a whole may be made after innumerable ornamental designs, or the holder with reversible lamp may be applied to any 50 of the existing forms of gas or electric lamp brackets now in use.

I do not confine myself to any special form of holder or chandelier, nor to the means herein specifically described for winding the cord 55 or forming the joints between movable portions of the lamp-holding frame, though I claim these specifically as parts of my invention, they forming the best and most practicable means of which I am at present aware for 60 carrying out the invention.

What I claim is—

1. The combination, with a chandelier, of a lamp-holder adapted to be used in an upright or inverted position, a shade for the lamp carried by the holder, arranged to be fixed or held above the lamp in either position of the holder, a flexible connection between the

holder and the chandelier, and a reel for the flexible connecting-cord or its equivalent, as set forth. 70

2. The combination, with a chandelier containing electric wires, of an electric-lamp holder and reversible lamp and shade supported thereby, a flexible cord containing insulated conductors and connecting the chandelier and the lamp-holder, a reel for taking up the flexible cord, and connections from the conductors in the cord to the wires of the lamp, as set forth. 75

3. The combination, with a chandelier containing electric wires, of an electric-lamp holder and reversible lamp and shade supported thereby, a flexible cord containing insulated conductors and connecting the chandelier and the lamp-holder, a reel within the 80 lamp-holder, upon which the cord is wound, and electrical connections from the conductors in the cord to the conductors of the lamp, as herein set forth. 85

4. The combination, with a chandelier containing electric wires, of a reversible electric-lamp holder and reversible lamp and shade supported thereby, a flexible two-wire cable connecting the lamp-holder with the chandelier, a reel within the lamp-holder, upon which the 90 cable is wound, and inclosed electrical connections from the conductors of the cable to those of the lamp, as described. 95

5. The combination, with a chandelier containing electric wires, of a reversible lamp-holder and reversible lamp and shade supported thereby, a flexible two-wire cable connecting the lamp-holder with the chandelier, a spring-actuated reel and locking-pawl within the lamp-holder, upon which the cable is 100 wound, and electrical connections from the conductors of the cable to those of the lamp, as set forth. 105

6. A reversible lamp-holder for incandescent lamps, consisting of a casing connected 110 by a flexible cable with a chandelier and containing a reel upon which said cord is wound, in combination with hollow arms supporting a reversible lamp and shade and containing the circuit-wires, all as set forth. 115

7. A reversible holder for incandescent lamps, consisting of a casing and supporting-base connected by a flexible cable with a chandelier, and containing a spring-actuated reel and locking-pawl, in combination with hollow arms, a bow-shaped tube carrying an incandescent lamp and shade, joined to said arms in such manner as to permit the lamp to be reversed in position, and electrical connections from the wires in the cable to the 120 conductors of the lamp, as herein set forth. 125

8. The combination, with casing *H* and base *K*, the spring-actuated reel and locking-pawl contained in said casing, and the flexible cable wound around the reel and connected to 130 a chandelier containing electric wires, of the branching frame or arms *N*, the bow *O*, carrying an incandescent lamp and shade pivoted to the arms *N*, means for retaining the

bow in given positions, and electric conductors extending through the bow O and arms N, and connecting the conductors of the cable with those of the lamp, as herein set forth.

5 9. The combination, with a chandelier containing electric wires, of a lamp-holder carrying a reversible electric lamp and formed with a casing, H, containing a spring-actuated reel and flexible cable connecting the 10 holder with the chandelier, the guide-rollers

M, and the base K, adapted to fit against the casing of the chandelier, or to support the holder when placed in an upright position on a stand.

In testimony whereof I have hereunto set 15 my hand this 20th day of February, 1885.

RAYMOND F. BARNES.
